UNITED STATES PATENT OFFICE.

ARTHUR E. JAMES, OF CRANSTON, RHODE ISLAND.

DEVICE FOR MOISTENING THE SOLES OF BOOTS AND SHOES.

1,113,638.

Specification of Letters Patent.

Patented Oct. 13, 1914.

Application filed March 10, 1914. Serial No. 823,829.

To all whom it may concern:

Be it known that I, ARTHUR E. JAMES, a citizen of the United States, residing at Cranston, in the county of Providence and 5 State of Rhode Island, have invented new and useful Improvements in Devices for Moistening the Soles of Boots and Shoes, of which the following is a specification.

This invention relates to a device for moistening the soles of boots and shoes, particularly adapted to be used in connection with bowling alleys where the players wish to moisten the soles of their boots to prevent slipping when they are bowling their ball 15 on the alley.

The object of the invention is to provide a neat and durable device of the character set forth which will enable a player to moisten the soles of his boots without getting the 20 uppers moistened, and also the object is to provide a device of the character described which is neat in its appearance, which is so constructed as to protect the interior from dirt of any kind and which can readily be 25 thrown open and cleansed whenever desired.

The invention consists in the combination and arrangement of parts set forth in the following specification and particularly pointed out in the claims thereof.

30 Referring to the drawings: Figure 1 is a plan view, partly in section, embodying my invention. Fig. 2 is a sectional elevation taken on line 2—2 of Fig. 1. Fig. 3 is a sectional elevation taken on line 3—3 of Fig. 1.

35 Like numerals refer to like parts throughout the several views of the drawings.

In the drawings, 5 is a casing divided into two chambers 6 and 7 by a partition 8 extending across the interior thereof. The 40 chamber 6 is adapted to contain water and preferably has a sponge 9 located therein, the sponge being saturated with water. A foot rest 10 of inflexible material is yieldingly supported over the sponge 9 in the 45 chamber 6 by means of springs 11, one of which is attached to each corner of said foot rest at its lower end, the upper ends of said springs being attached by screws 12 to the casing 5. The distance to which the foot 50 rest 10 may be moved upwardly by the springs 11 is limited by stop-rods 13 which extend across the chamber 6 above the foot rest 10 and are fastened at their opposite ends to the casing 5. The foot rest 10 is 55 provided with perforations 14 for the purpose of allowing the water to pass through

said foot rest and against the sole of the boot as hereinafter described.

The casing 5 is provided on opposite sides thereof with openings 15 located above the 60 foot rest 10, so that the foot of the user may be inserted within the chamber 6 and placed upon the foot rest 10 preparatory to the moistening operation.

A cover 16 is hinged at 17 to the casing 5 and this cover extends over both of the chambers 6 and 7 and is provided with a semi-cylindrical portion 18 located above the foot rest 10 to give more space for the foot of the user to be inserted in said chamber 6. 70 The cover 16 is also provided with a hole 19, said hole being surrounded by a conical flange 20.

A cuspidor 21 is provided in the chamber 7. The cover 16 is held in its closed position 75 by means of a spring catch 22.

The operation of the device hereinbefore specifically described is as follows: The sponge 9 is saturated with water and placed in the chamber 6 beneath the foot rest 10. 80 The user of the device places his foot on the foot rest 10 and presses downwardly thereon, thus compressing the sponge and causing the water to flow up through the perforations 14 against the sole of the boot, whereby the 85 sole is moistened. If, while the user of the device is moistening the sole of his boot, he desires to expectorate, he may do so by using the cuspidor 21, and it will be noted that when so using the cuspidor the upper of the 90 boot which is being moistened is fully protected against any accidental moistening thereof by expectoration of the user. Thus it will be seen that when the boot is in position to have the sole thereof moistened, the 95 upper is protected and kept clean from any accidental moistening by means of the cover 16, the device thus being constructed so that the different parts coöperate to moisten the sole of the boot and simultaneously prevent 100 the upper from being moistened accidentally under the ordinary conditions of use.

It will be understood that one of the important features of my invention consists in providing a cover for the chamber containing the moistening apparatus for the sole of the boot, for the reason that where these devices are used the players will throw cigars into any receptacle of the sort which may be handy and the cover prevents the defiling of the interior of the device, while at 105 the same time said cover leaves the device 110

open at the sides so that the boot can be inserted and the sole thereof moistened.

Having thus described my invention what I claim and desire by Letters Patent to secure is:

1. A device for moistening the sole of a boot or shoe having, in combination, a casing provided with a chamber adapted to contain water, a perforated foot rest of 10 flexible material located in said casing above said chamber and yielding means arranged to support said foot rest above said chamber.

2. A device for moistening the sole of a 15 boot or shoe having, in combination, a casing provided with a chamber adapted to contain water, a perforated foot rest in said casing above said chamber, and springs arranged to support said foot rest above said 20 chamber.

3. A device for moistening the sole of a boot or shoe having, in combination, a casing provided with a chamber adapted to contain water, a perforated foot rest in said 25 casing above said chamber, a sponge located in said chamber, and yielding means arranged to support said foot rest above said chamber.

4. A device for moistening the sole of a 30 boot or shoe having, in combination, a casing provided with a chamber adapted to contain water, a perforated foot rest in said casing above said chamber and yielding means arranged to support said foot rest 35 above said chamber, said casing having an opening in one side thereof above said foot rest through which said boot may be inserted.

5. A device for moistening the sole of a 40 boot or shoe having, in combination, a casing provided with a chamber adapted to contain water, a perforated foot rest in said casing above said chamber, yielding means arranged to support said foot rest 45 above said chamber and a stop adapted to engage said foot rest and limit the distance to which said foot rest may be moved by said yielding means.

6. A device for moistening the sole of a 50 boot or shoe having, in combination, a casing provided with a chamber adapted to contain water, a perforated foot rest in said casing above said chamber, yielding means arranged to support said foot rest above

said chamber and a cover for said casing extending entirely across and above said foot rest, there being a space between said cover and foot rest into which the boot of the user may be inserted. 55

7. A device for moistening the sole of a 60 boot or shoe having, in combination, a casing provided with a chamber adapted to contain water, a perforated foot rest in said casing above said chamber, yielding means arranged to support said foot rest above said 65 chamber, said casing having an opening in one side thereof above said foot rest through which said boot may be inserted and a cover hinged to said casing and extending over said chamber, said cover provided with a 70 hole and a receptacle in said casing beneath said hole.

8. A device for moistening the sole of a boot or shoe having, in combination, a casing provided with a chamber adapted to 75 contain water, a perforated foot rest in said casing above said chamber, yielding means arranged to support said foot rest above said chamber, said casing having an opening in one side thereof above said foot rest 80 through which said boot may be inserted and a cover hinged to said casing and extending over said chamber, said cover provided with a hole, a conical flange on said cover surrounding said hole and a receptacle 85 in said casing beneath said hole.

9. A device for moistening the sole of a boot or shoe having, in combination, a casing provided with a chamber adapted to contain water, a perforated foot rest in said 90 casing above said chamber, yielding means arranged to support said foot rest above said chamber, said casing having an opening in one side thereof above said foot rest, a cover for said casing extending over said 95 chamber and having a semi-cylindrical portion located above said opening in the side of said chamber, whereby a boot may be inserted beneath said cover and above said foot rest for the purpose specified. 100

In testimony whereof I have hereunto set my hand in presence of two subscribing witnesses.

ARTHUR E. JAMES.
